HARRY W. BUTTERWORTH, JR., OF PHILADELPHIA, AND WILLIAM E. H. BELL, OF GLENSIDE, PENNSYLVANIA, ASSIGNEES TO H. W. BUTTERWORTH & SONS COMPANY, OF PHILADELPHIA, PENNSYLVANIA, A CORPORATION OF PENNSYLVANIA

APPARATUS FOR FLUID TREATING OR DYEING YARNS

Application filed January 10, 1930. Serial No. 419,908.

This invention relates to apparatus for fluid treating or for dyeing yarns and more particularly to an apparatus especially adapted for use in denitration of nitro-cellulose yarns.

An important object of the invention is the production of apparatus of this character permitting ready insertion and removal of the yarn, providing for thorough contact of the yarn with the treating fluid and reducing the quantity of treating fluid which must be employed.

A further and more specific object of the invention is to produce a novel and improved yarn support facilitating the installation of the yarn in juxtaposition to a plurality of spray pipes for treating the same and provide a means for automatically connecting said spray pipes with a supply system upon insertion of the yarn support in the treating vat.

A further object of the invention is to provide an apparatus of this character, novel and improved, for maintaining the yarn in position upon the yarn supports while imparting rotation to the yarn supports to insure subjection of all parts of the yarn skeins to the treating fluid.

These and other objects we attain by the construction shown in the accompanying drawings, wherein for the purpose of illustration, we have disclosed a preferred embodiment of the invention and wherein:

Fig. 1 is a side elevation of apparatus for treating yarns, constructed in accordance with my invention, the yarn supporting unit being illustrated as partially withdrawn;

Fig. 2 is a longitudinal sectional view therethrough on line 2—2, Fig. 4;

Fig. 3 is a plan view thereof;

Fig. 4 is a section on the line 4—4, Fig. 2;

Fig. 5 is a section on the line 5—5, Fig. 2;

Fig. 6 is an enlarged detail sectional view through one of the spray tubes, having a yarn stick mounted thereon; and

Fig. 7 is a perspective view partially broken away of the yarn supporting unit, with the yarn partially applied thereto.

Referring now more particularly to the

drawings, the numeral 10 generally designates a vat provided centrally with one or more inlets 11 in its bottom wall 12. Where more than one inlet is employed, as in the present instance, these inlets will be transversely aligned and the upper ends of the inlets will be formed as one element of a coupling as indicated at 13.

At opposite sides of the inlets the bottom wall is provided with depressions forming sumps 14 having outlets 15. At one side of the vat and preferably supported from a continuation 16 of the bottom thereof is a pump 17, the inlet of which is connected through a conduit 18 with outlets 15 of the sumps, and the discharge line 19 of which is connected to the inlets 11. The side walls of the vat are provided centrally with vertically extending pairs of spaced ribs 20. From the top of each side wall to a point adjacent the bottom thereof, the wall is grooved as at 21, grooves 21 inclining toward one another at their lower ends.

The yarn support comprises a header 22, the lower end wall of which is provided with inlets 23, defined at their lower ends by downwardly tapering bosses seating upon the tapered seats 13. These bosses are guided into engagement with the seats by engagement of flanges 25 upon the edges of the header with the inner faces of the ribs 20. The width of the header is reduced at the upper end thereof as at 26, thereby producing upwardly facing shoulders 27. Extending through the upper wall 28 of the header, which is relatively thick, are spray tubes 29, each communicating with the interior of the header and each having its outer end closed as at 30. Apertures 31 formed in these tubes provide for dissemination of fluid delivered thereto in the desired directions.

The upper wall of the header is surmounted by a bar 32 having vertical shafts 33 corresponding in number and arrangement to the tubes 29, rotatably directed therethrough. Each shaft 33 is equipped upon its opposite ends with bevel gears 34, the lower bevel gears of the shaft operating in recesses 35 formed in the upper wall 28.

of the header and projecting to opposite side faces thereof as is clearly shown in Fig. 2. Bar 32 has on its upper surface, longitudinally spaced bearings rotatably mounting the shaft 37. This shaft has secured thereto, pairs of oppositely directed bevel gears 38, the gears of each pair co-acting with adjacent sides of a pair of gears 34 upon the upper end of shafts 33.

10 Removably mounted on opposite ends of the spray tubes 29 are skeletal yarn sticks 39, each comprising inner and outer heads 40 and 41 and a circumferentially extending series of rods 42, the inner faces of which 15 are spaced from the walls of the spray tube, so that the fluid may pass freely from the openings 31. The inner heads 40 are formed as bevel gears at 43 for co-action with the bevel gears 34 upon the lower ends of 20 shafts 33. Yarn sticks 39 may be bodily removed from the spray tubes 29 by simply slipping them over the outer ends thereof.

Directed through and supported centrally by the bar 32 are spray tubes 44, a spray tube 44 being arranged between each pair of shafts 33 and being provided with spray openings directing the fluid downwardly against the yarn sticks of a pair of adjacent tubes 29. The center portion of each 25 spray tube is in communication with the interior of the header 22 through a port 45 formed in the upper wall of the header and in the bar 32. Opposite sides of the header have each threaded therein adjacent the bottom thereof, the inner ends of a transversely 30 extending series of spray tubes 46, the spray tubes being longitudinally directed and as in the case of spray tubes 29 and 44 having their outer ends closed. Spray tubes 46 correspond in number and arrangement to the 35 spray tubes 29 and each underlie an end of a tube 29.

In use of an apparatus of this character, when the apparatus is to be charged, the 40 yarn supporting unit consisting of header 22, bar 32, and the spray pipes, is removed from the vat which may be conveniently done by engaging a hoisting mechanism with a bail 47 connected to the bearings 36. The 45 skeins S of yarn have been applied to the several yarn sticks and are held stretched through a pipe or other tubular form 48 and each yarn stick with this form in position is slid over its spray tube 46, after 50 which the form may be removed. When all of the yarn sticks have been applied, the unit is partially lowered into the vat; guard sticks 49 are placed in the vat with their ends engaged in the grooves 21 and guards 55 50 are then placed over the upper ends of the end walls of the vat. Each of these guards comprises a clamp section 51 to embrace the upper edge of the wall, a resilient section spaced from the inner face of the wall and 60 adapted to abut the outer end face of the

outer end head of the yarn stick and yieldingly urge the yarn stick inwardly when the unit is fully inserted and a projecting flange 52 upon the lower end of the resilient section adapted to underlie the inner end of the yarn stick and to bear against the upper portion of the outermost yarn skeins upon the stick. The lowering of the unit is then complete, the final lowering movement placing the tapered bosses into engagement with the guards. Attention is directed to the fact that the passage of the yarn at the inner ends of the sticks over the inner end heads and engagement with the gearing will be effectually prevented by the fact that these skeins will engage against the side faces of the header and the heads 43 will be located over shoulders 27. Shaft 37 is then rotated and operation of pump 17 started with the result that a spray of the treating fluid is directed against the inner faces of the skeins as they are moved through the yarn sticks by spray tubes 29 and 49 and a spray is directed against the outer faces thereof by the spray tubes 44. 80 Attention is also directed to the fact that because of the gearing arrangement provided, adjacent faces of the yarn skeins will be traveled in the same direction so that these yarn skeins can be brought into much closer relation without danger of tangling thereof. Treating fluid delivered to the vat by the spray tubes 29, 44 and 46 will pass sumps 14 and be again restored to circulation by pump 17. 90

False bottoms "B" disposed in the upper ends of the sumps and supported from the bottom wall of the casing prevent the suction of the pump from disturbing the yarn. It will be understood that while we have 105 above referred to a "spray" of the treating fluid, there is no actual spray, the entire casing being filled with the treating fluid and the spray from the tubes 44 merely acting to provide a constant agitation of the 110 fluid which maintains a uniform balance as regards temperature and density and insures proper penetration of the bath through the skein.

It will be obvious that a construction of 115 this character comprises a very compact arrangement in which the yarn may be very readily and rapidly placed and removed. It will also be obvious that this construction is capable of a considerable range of change 120 and modification without in any manner departing from the spirit of our invention, and we do not wish to be understood as limiting ourselves thereto except as hereinafter claimed. 125

We claim:

1. In yarn treating apparatus, a vat, a 130 yarn support adapted to be inserted in the vat, said yarn support including a centrally-disposed header, tubular members extending

- through and communicating with the header and having their ends formed as spray tubes, skeletonic yarn sticks rotatable upon said spray tubes, means carried by the header 5 for rotating said yarn sticks, said yarn sticks being removable from the spray tubes by outward axial movement thereon, and means carried by the ends of the vat and yieldably engaging the outer ends of the 10 yarn sticks for maintaining the inner ends of the yarn sticks in co-operative engagement with said rotating means.
2. In yarn treating apparatus, a yarn support comprising a header, a spray tube supported at one end by and communicating with the header, a skeletonic yarn stick positionable upon said spray tube by an axial movement from the opposite end thereof, and a vat receiving said yarn support including means engaging the yarn stick to maintain the yarn stick in position upon the spray tube.
3. In yarn treating apparatus, a yarn support comprising a header, a spray tube supported at one end by and communicating with the header, a skeletonic yarn stick positionable upon said spray tube by an axial movement from the opposite end thereof, a vat receiving said yarn support and means supported from the vat engaging the yarn stick to maintain the yarn stick in position upon the spray tube and a deflector to extend beyond the inner end of the yarn stick and engage the outermost skein of yarn carried thereby.
4. In yarn treating apparatus, a yarn support comprising a header, a spray tube supported at one end by and communicating with the header, a skeletonic yarn stick positionable upon said spray tube by an axial movement from the opposite end thereof, a vat receiving said yarn support and means supported from the vat engaging the yarn stick to maintain the yarn stick in position upon the spray tube and a deflector to extend beyond the inner end of the yarn stick and engage the outermost skein of yarn carried thereby, said deflector comprising an extension of the first-named means.
5. In yarn treating apparatus, a yarn support comprising a header, a spray tube supported at one end by and communicating with the header, a skeletonic yarn stick positionable upon said spray tube by an axial movement from the opposite end thereof, a vat receiving said yarn support and means supported from the vat engaging the yarn stick to maintain the yarn stick in position upon the spray tube and a deflector to extend beyond the inner end of the yarn stick and engage the outermost skein of yarn carried thereby, said deflector together with the first-named means being removable in its engagement with the vat.
6. A yarn support comprising a head-
- er, spray tubes projecting therefrom, rotatable skeletonic yarn sticks surrounding said spray tubes and adapted to support skeins of yarn, means for rotating said yarn sticks, and a further series of spray pipes corresponding in number and arrangement to the first-named spray pipes and adapted to extend through the lower ends of yarn skeins supported from the corresponding yarn sticks. 70
7. A yarn support comprising a header, spray tubes projecting therefrom, rotatable skeletonic yarn sticks surrounding said spray tubes and adapted to support skeins of yarn, means for rotating said yarn sticks, other spray pipes likewise communicating with the header and extending over said yarn sticks, and a further series of spray pipes corresponding in number and arrangement to the first-named spray pipes and adapted to extend through the lower ends of yarn skeins supported from the corresponding yarn sticks. 80
8. In yarn treating apparatus, a vat having an inlet and an outlet, a pump having its intake communicating with the outlet and its discharge communicating with the inlet and a yarn support insertable in the vat including spray pipes and a header communicating with said spray pipes having an inlet coming into sealing engagement with the inlet of the vat when the yarn support is inserted therein. 90
9. In yarn treating apparatus, a vat having an inlet and an outlet, a pump having its intake communicating with the outlet and its discharge communicating with the inlet and a yarn support insertable in the vat including spray pipes, a header communicating with said spray pipes having an inlet coming into sealing engagement with the inlet of the vat when the yarn support is inserted therein, skeletonic yarn sticks rotatably mounted upon said spray tubes and means carried by the header for rotating said yarn sticks. 100
10. In a yarn treating apparatus, a vat having an inlet, means for supplying treating fluid to the inlet, a yarn support removably associated with the vat including a header having an inlet, the inlets of the header and vat being constructed as co-acting elements of a coupling and co-acting means upon the header and the vat for guiding the inlet of the header in its engagement with the inlet of the vat. 115
11. In yarn treating apparatus, a yarn support comprising a header, a spray tube supported at one end by and communicating with the header, a skeletonic yarn stick mounted on said spray tube, said yarn stick being free for axial movement and being removable from the spray tube by such axial movement and a vat to receive said yarn support having means engaging the 125
- 130

yarn stick to maintain it in position upon the spray tube.

12. In yarn treating apparatus, a yarn support comprising a header, a spray tube supported at one end by and communicating with the header, a skeletal yarn stick mounted on said spray tube, said yarn stick being free for axial movement and being removable from the spray tube by such axial movement, a vat to receive said yarn support having means engaging the yarn stick to maintain it in position upon the spray tube, and means for rotating said yarn stick.
13. In yarn treating apparatus, a yarn support comprising a header, a spray tube supported at one end by and communicating with the header, a skeletal yarn stick mounted on said spray tube, said yarn stick being free for axial movement and being removable from the spray tube by such axial movement, a vat to receive said yarn support having means engaging the yarn stick to maintain it in position upon the spray tube, and means for rotating said yarn stick comprising co-acting drive elements on the support and yarn stick, the means of the vat maintaining operative engagement between said co-acting elements.
14. In yarn treating apparatus, a vat having an inlet, a bodily removable header associated with and insertable in the vat, said header including spray tubes, yarn supports associated with the spray tubes, said header communicating with the spray tubes and having an inlet and co-acting guide means upon the header and vat whereby the inlet means of the header and vat are automatically brought into communication when the header is inserted in the vat.
